Filed June 5, 1970, Ser. No. 23,324

Term of patent 14 years

Int. Cl. D6—99

U.S. Cl. D33—17

FIG. 1 is a top plan view of a holder for washing pots and pans showing my new design.

FIG. 2 is a rear elevation thereof.

FIG. 3 is an elevation taken from the right side thereof.

FIG. 4 is a front elevation thereof.

The fragmentary broken line representation of the front of a sink in FIGS. 1 and 3 is for purposes of illustration only.

I claim:

The ornamental design for a holder for washing pots and pans, as shown and described.
